UNITED STATES PATENT OFFICE.

TRAY DAVIS, OF BERKELEY, CALIFORNIA, ASSIGNOR TO BUNTING IRON WORKS, OF SAN FRANCISCO, CALIFORNIA, A CORPORATION OF CALIFORNIA.

OIL BURNER.

Application filed May 8, 1923. Serial No. 637,434.

This invention relates to liquid fuel burners, and more particularly to an oil burner that is arranged to be supported on the outside wall of a combustion chamber and to be moved into proper position, with the nozzle extending into the chamber. Oil burners of this general construction are now well-known, and are extensively used for example in the generation of steam for use in power plants or in house heating plants.

There are usually correlated with the burner itself a pump for supplying the liquid fuel to the nozzle, as well as a fan for assisting the formation of a fuel spray. To insure against an accumulation of unused fuel, it is customary to provide for a fuel return. It is one of the objects of my invention to provide a fuel supply and return system of simple and inexpensive construction.

It is another object of my invention to improve in general the construction of oil burners of this type.

In order that the liquid fuel be completely burned in the combustion chamber, sufficient air must be introduced for this purpose. If excessive air is introduced, however, the result is objectionable because of the absorption of heat thereby. Another element that should be varied with the rate or burning is the rate at which air is supplied for atomizing and projecting the fuel spray. It is another object of my invention to provide for a regulation of these features in response to the regulation of the fuel fed to the device.

It is still another object of my invention to support the entire oil burner in a manner that will readily permit the combustion chamber to be cleaned. This I accomplish by providing a comparatively large-sized hinged door for the combustion chamber, on which door in turn is hinged the oil burner. Thus when it is desired merely to inspect the burner or the combustion chamber, or to start the burner operation, the large door is left closed, and the burner alone is swung out of the combustion chamber on its pivots on the door. If it should be necessary to repair or clean the combustion chamber, the hinged door is moved so as to expose a comparatively large opening.

Oil burners usually employ a draft of air to project the spray of fuel from the edge of

a rotating cup. This cup throws off the atomized fuel by centrifugal force, and the draft of air is intended to direct this fuel to the interior of the combustion chamber. It is another object of my invention so to direct this air draft that less power for driving the air will be needed for accomplishing this result satisfactorily.

My invention possesses other advantageous features, some of which with the foregoing will be set forth at length in the following description, where I shall outline in full that form of the invention which I have selected for illustration in the drawings accompanying and forming part of the present specification. Although I have shown but one embodiment of my invention in the drawings, it is to be understood that I do not desire to be limited to that form, since the invention as set forth in the claims may be embodied in other forms also.

Referring to the drawings:

Figure 1 is a front view of an oil burner embodying my invention, shown as installed on the door of a steam generating boiler;

Fig. 2 is a side view, partly in section, of the oil burner shown in Fig. 1, but installed on a furnace wall;

Fig. 3 is a front view of the burner shown in Fig. 2, with some of the parts broken away and others in section, so that the construction may be more clearly indicated;

Fig. 4 is a fragmentary elevational view, showing the fuel valve and its associated parts, used on the oil burner of Figs. 1 and 2;

Fig. 5 is a sectional view along the plane 5-5 of Fig. 4;

Fig. 6 is a perspective view of the fuel inlet controlling device, used in connection with the fuel valve of Figs. 4 and 5;

Fig. 7 is a sectional view along plane 7-7 of Fig. 3;

Fig. 8 is a sectional view along plane 8-8 of Fig. 3;

Fig. 9 is a fragmentary view of one form of the invention, in which an opening in the combustion chamber through which the oil nozzle is adapted to extend is formed by a stationary member, instead of by a door as indicated in Fig. 1; and

Fig. 10 is a fragmentary sectional view of a modification of my invention.

The general arrangement of a boiler in-

stallation utilizing an oil burner of my invention, is shown in Fig. 1. In this arrangement the boiler 85 is shown as arranged above a combustion chamber 86. The oil burner 87 is supported externally of the chamber 86, although its fuel burning parts extend through one of the walls of chamber 86, where they serve to burn the fuel and produce a temperature capable of operating the boiler 85. The external arrangement of all of the control parts of the burner 87 renders it capable of ready control, as by the aid of a pressure governor 88, indicated merely diagrammatically in Fig. 1. In order that the mode of control may be well understood, it is first of all necessary to describe the construction of the oil burner parts more in detail. For this purpose the succeeding figures have been provided on the drawings.

I show, in Fig. 2, an oil cup 11 which may be of conical form, and which extends through an opening in the wall 12 of the combustion chamber 86. This oil cup or nozzle 11 is preferably rotatable, and for this purpose it is appropriately fastened to a rotating shaft 13, as by aid of the threaded extension 14, which engages a tapped hole in an intermediate wall 15 of the cup 11. This wall is pierced by a plurality of apertures 16, for permitting oil to flow to the enlarged end of the cup 11. As is well understood, the rotation of the cup 11 causes centrifugal force to throw off the oil in a spray at the large end of the cup. In order to restrict this spray of oil into a comparatively narrow path, as well as to assist in the formation of the spray, a draft of air is directed past the outer end of the cup 11, between a nozzle 17 surrounding the cup 11, and the outer surface of a deflector 128. The interior surface of nozzle 17 is formed to provide an annular passageway for the air draft, in combination with the annularly arranged deflector 128. This deflector may be supported around the cup 11 by the aid of a plurality of bosses or projections 123 which are formed integral with the external active surface of the deflector and serve to space it from the interior of the nozzle 17. The annular passageway 124 formed between the nozzle 17 and the deflector 128 is directed inwardly toward the axis of the cup, and the air blown therethrough is caused to converge thereto. The direction of this blast is of great importance, since it prevents the flaring out of the fuel spray from the edge of cup 11 under the influence of centrifugal force, without the necessity of a powerful air blast. From another aspect, the inward direction of the air blast causes it in some measure to neutralize the centrifugal force of the spray; and less force is required in an axial direction to prevent deposition of unconsumed

fuel on the wall 12 of the combustion chamber. This centrifugal force is of course useful only for spraying or atomizing the fuel, and after the spraying is accomplished, it is desirable to minimize its effects as much as possible.

The particular details of the nozzle 17 may be varied somewhat while still using it for directing an inward blast of air. For example, another form of nozzle is illustrated in Fig. 10 for accomplishing this result. In this instance the nozzle 125 is formed with an integral baffle 126 for directing the air to the high part of nozzle 125. From there the air escapes through a series of drilled apertures 127 directed inwardly toward the axis of cup 11, and past its outer edge.

The draft of air conducted by either of nozzles 17 or 125 past the edge of cup 11 may be conveniently produced by a fan 18, which is preferably rotated by the shaft 13 which rotates the cup 11. The fan 18 is of the centrifugal type, and may comprise a spider 19 keyed to an enlarged portion 20 of shaft 13. This spider has a hollow hub 89 to which are attached the spaced fan forming discs 21. Between the discs there may be radial partitions for driving off the air, constructed and arranged in any well understood manner.

To provide appropriate passages for the air driven off between the discs 21, into the nozzle-like member 17, the fan is encased in a casing formed in this instance of a front casing member 22 and a rear casing member 23, which when fastened together form a substantially tight chamber for the fan 18. These members 22 and 23 may be conveniently made of castings, and may be fastened together by the aid of bolts 24 passing through lugs 25 cast integral with the casing members 22, 23. The fan casing forms in addition the support for a large part of the burner structure. Thus on the rear member 23 a boss 26 is provided for the hollow tube 27, which is adapted to support the nozzle 17, as by the aid of interengaging screw threads 28. A tapered aperture 29 through the rear casing member 23 connects with the interior of the tube 27 and the nozzle 17, and in this way a continuous, gradually decreasing air passage is obtained from the interior of the fan casing to the outer end of the oil cup 11. In order further to guide the air properly from the fan, radial ribs 122 may be formed on the rear casing member 23. For the air intake, the front casing member 22 is provided with an aperture 30, shown in this instance as axial, which connects the interior of casing 25 with the external atmosphere, by way of the hollow hub 89 of spider 19. The air supplied by the fan 18 for best results should be varied in accord-

ance with the intensity of combustion, so that as more fuel is used, more air is supplied by the fan. This is essential in order to produce complete combustion without 5 excess air at all times, and also to project the oil spray. In order that this air supply may be readily controlled, a shutter 90 is provided for the air inlet 30, which shutter is shown as rotatable in a guide 91. 10 This guide has appropriate openings 92 therein which are adapted to be closed more or less by the shutter 90. This shutter arrangement is shown in the present instance as concentric to the shaft 13, as well as to 15 the hub 89 of spider 19. In order to move the shutter 90 a weighted lever arm 93 is provided, attached in any appropriate manner to the shutter, and capable of movement in a circle around the axis of the 20 shutter.

The shaft 13, which drives the fan 18 and the cup 11, is arranged to be driven by any appropriate source, such as a small electric motor 31. This motor may be conveniently carried on a bracket 32 fastened to the front of fan casing 25. A pump 33 for the fuel may also be supported on this bracket in a position convenient for connection to the shaft 13, so that it too may 30 be driven by the same source of power as the fan 18 and cup 11. Since the particular details of the motor 31 and of the pump 33 form no part of my present invention, I shall not describe these parts in detail. It 35 is sufficient for the present purpose to specify that the pump may conveniently be of the type that utilizes intermeshing gears for forcing the liquid into the supply pipe system of the oil burner.

To permit the oil burner to be removed 40 from the furnace so as to expose the cup 11, the entire fan casing 22-23 is pivoted at one side of the combustion chamber opening. As shown most clearly in Fig. 1, the 45 fan casing 22 is pivotally supported on a swinging door 94, in which an opening may be provided for permitting the cup 11 to project within the combustion chamber 86. In Figs. 2 and 3 a slightly different form 50 of wall opening is shown, in which the door 94 is omitted, but instead a frame 34, permanently attached to the combustion chamber opening, is shown. However, in each 55 form the opening which permits entry of the oil burner cup 11 into the combustion chamber 86, is the same, and therefore at this point, only that form of the combustion chamber opening, illustrated in Figs. 2 and 3, will be described. The door frame 60 34 illustrated in Figs. 2 and 3, is shown in greater detail in Fig. 9. This door frame in the present instance has a rectangular opening 35, through which the oil nozzle parts may extend as shown in Fig. 2. The 65 frame is appropriately fastened to the wall

12 of the combustion chamber, as by the aid of bolts 36. The aperture 35 in the door frame registers with a corresponding aperture in the wall 12. Furthermore, to strengthen the door frame casting to a sufficient degree, and to form a guide to the brick mason in laying the bricks of the furnace wall, vanes or ribs 37 are provided, one on each side of the aperture 35, which ribs extend for a substantial distance into 70 the aperture in wall 12. Other shallower ribs such as 38 may also be provided on the back of the door frame 34. The lugs 39 are located to the right of this frame, upon which lugs the fan casing 22-23 is 75 pivoted. As shown in Fig. 3, the fan casing is provided with corresponding hinge lugs 40, and each pair of lugs is provided with a pivot pin 41, which extends almost entirely through both lugs of each pair. 80

In order to hold the entire fan casing 22-23 and its associated parts in proper closed position, a latch 42 is used, which is pivoted to lugs 43 on the door frame 34. This latch has a sloping face 44 which is engaged by the casing 22 as it is shut. An abrupt face 45 drops back of the fan casing as soon as this casing reaches its closed position. This closed position is determined by the spacers 81 cast on the rear face of casing member 23, which serve to maintain an air space between this member and the wall 12. To urge the latch 42 to closed position, a compression spring 46 is provided, which is guided by the bosses 47, 48 respectively on the door frame 34 and the latch 42. Furthermore, a stop 95 on the latch prevents it from being urged too far by the spring 46. The pump 33 is directly connected to the 95 motor shaft and thus rotates therewith. The amount of oil delivered to the burner nozzle is regulated by operation of a valve such as 59, interposed between the pump and the nozzle. Since the amount of oil delivered to the nozzle is variable and the speed of 100 the pump is usually constant or is incapable of variation with the same degree of fineness as the oil flow, the arrangement is purposely made such that an excess of oil is discharged by the pump, so that even for the maximum demand, sufficient oil may be provided. Then excess oil is caused to flow 105 back to the oil supply tank. It is necessary therefore that two pipes, the supply pipe and the return pipe, extend from the source of supply to the pump, providing two conduits, the continuity of which should not be interrupted by movement of the burner structure in and out of the combustion chamber 86. It has been customary to pass these two pipes through the hinges of the burner structure, using the pipes as hinge pins and providing rotatable connections on the pipes on the burner structure side of the hinge, so that the structure can be swung on 110

115

120

125

130

the hinges without interrupting the continuity of the pipes. In such a construction, the supply and return pipes are usually disposed at right angles to the hinge axis, and the 5 plumber, in connecting these pipes to the conduit hinge pin, frequently takes up too much on the pipes and strains the hinge, so that it does not function properly. This improper installation is very apt to result in 10 leaks in the suction pipe, and the discharge pipe. Since the suction pipe must be maintained air tight in order to supply oil to the burner, it becomes readily apparent how disadvantageous such a construction may become. Leaks in the discharge pipe also are 15 objectionable because they augment the loss of oil and besides produce disagreeable unsightly conditions in the neighborhood of the hinges. It is my object to teach how the 20 construction may be changed so as to overcome these and other objections. In accordance with my construction, the conduits do not pass through the hinges and are clamped to the blower casing so that they cannot be 25 pulled out of line. As shown most clearly in Figs. 3 and 8, I may employ a stationary pipe fitting 95', the main axis of which is preferably substantially coincident with that of the pins 41. A lower axial passage 30 49 in this fitting 95' communicates with a radial passage 50, and is used in this instance to feed oil to the suction side of pump 33. For this purpose a feed pipe 51 is appropriately fastened, as by screw threads, 35 into the passage 50. An offset pipe fitting 52 is rotatably mounted on the lower extremity of the fitting 95'; in order to permit rotation without leakage a packing 53 is used, held around fitting 95' by the aid of 40 a hexagonal union nut 54 engaging the threaded external periphery of the offset 52. By the aid of this construction, the swinging of the fan casing 22 to and from the wall opening merely causes a corresponding 45 swinging movement of the offset 52 with respect to the stationary fitting 95'.

From the outer end 55 of the offset 52, appropriate piping 56 is provided for connecting the offset to the intake 96 of pump 33. From the discharge end 57 of this pump, there are two paths for the oil—through the biased valve structure 58 back to the oil tank or reservoir, or through a hand-operated valve 59 to the oil burner 55 cup 11. The biased valve structure 58 and the return are provided to reconduct all the unused oil to the tank, and these elements operate automatically upon the production of a sufficient degree of pressure at the discharge end 57 of the pump 33. The biased valve 58 may be of any well known construction; for example it may utilize a compression spring 60 to urge valve 61 upon its seat 62. After the oil gets beyond this valve, it 60 flows through piping 63 to an offset 64 en-

tirely similar to the offset 52 already described. This offset is likewise rotatably supported upon the upper end of the stationary fitting 95', and is in communication with the axial opening 65. This opening in turn 70 communicates with the radial opening 66, into which a pipe 67 is threaded for returning the oil to the tank or reservoir.

In order to prevent the stationary fitting 95' from buckling in response to a stress 75 up on the pipes 51 and 67, straps 68 are provided, cast integral with the fan casing 22, and embracing the fitting 95' on each side of the point where the pipes 51 and 67 enter. There is a cap 69 for each strap 68. The 80 arrangement is such that relative rotative movement between these straps and the fitting 95' is possible.

The oil which is to be burned at the nozzle flows through the manual control valve 59, 85 The details of the hand controlled valve 59 and of its associated parts are most clearly illustrated in Figs. 4, 5 and 6. In these figures the valve structure is shown as cast integral with the biased valve 58; this combined structure is very compact. The manual control is preferably supplemented by a control responsive to the boiler conditions, as for instance by the pressure governor 88 of Fig. 1. For this purpose a hollow valve 90 sleeve 97 is rotatably supported within the valve structure 59, in such a way that its axis intersects that of the valve port 71. The opening of this valve port is controlled by the handle 98, but the oil before it can 100 proceed further must also pass through the sleeve 97, in which a triangular opening 99 is provided for this purpose. This triangular opening is located at such a point on the sleeves that it cooperates with the side 105 walls of port 71 to control the extent of the opening between the port 71 and the interior of the tube 97. Thus by rotating the sleeve 97 by a limited amount, the port opening 110 may be varied. This rotation is effected by the aid of a stem 100 which is journaled in the valve structure 59 and which has an extending squared portion 101. A packing nut 102 prevents leakage of oil past the bearing of this stem 100. Attached to the squared portion 101 is an operating lever 106 which has an extension 103 operating between the limiting stops 104. These stops are formed by cap screws adjustable in lugs 105 on the valve structure 59, and serve to limit the rotation of sleeve 97.

The lever 106 has another extension 107 which serves for the attachment of the weighted operating rod 108, shown most clearly in Fig. 1. This rod is connected mechanically to the pressure governor 88, by any appropriate device, such as a chain or wire 109. The arrangement is such that the supply of oil is so controlled by this pressure governor and ele- 130

ments 108, 106, and 97, that a constant predetermined pressure is maintained. In other words, upon an excessive increase in pressure, the rod 108 is rotated in such a direction as to decrease the oil opening, while a decrease in pressure will cause the oil opening to increase in extent. I also prefer to control simultaneously the opening of the hinged damper door 111 at the bottom of the combustion chamber. For this purpose a connection 112 is provided between the door 111 and any appropriate portion of the control mechanism, as for example, to the lever 108. Simultaneously with this control, the air intake to fan 18 is controlled by the aid of a connection 110 between the governor 88 and the shutter lever 93. The amount of air delivered both by the fan and through the door 111 is proportioned properly to the rate of combustion of the oil, so that there is just sufficient air introduced to cause complete combustion. While of course this effect could be obtained by simply controlling either the opening of door 111 or the air intake to fan 18, I prefer to accomplish this by a combined control as shown, so that the control of the fan intake may serve also to control the speed of projection of the oil by the fan blast from the cup 11.

After the fuel passes into tube 97 by way of the opening 99, it is permitted to flow through an elbow 113 (Figs. 2 and 5) fastened to the valve structure 59 so that one of its arms is aligned with the hollow tube 97. Into this elbow extends a supply tube 72, preferably made of copper. This tube 72 extends downwardly, as shown in Fig. 2, and then radially back of the rear casing member 23, as shown most clearly in Fig. 3. It then extends through the aperture 35, the wall of which is cut away to form a lip 73 of conical form, with its axis extending upward and to the rear. This lip is shown most clearly in Fig. 9. Finally the pipe 72 enters the tube 27, which has an integral interior boss 74 joined to the wall of the tube by an extension 75. Through this extension an aperture 76 is provided, which serves to place the pipe 72 in communication with an oil tube 77. This tube may be appropriately anchored in the boss 74, and as shown in Fig. 2 it extends into the oil cup 11, so that oil coming through this pipe is forced through the apertures 16 in the wall 15. Contact between the oil and shaft 13 is prevented by a tube 78 serving as a hood and held concentrically with tube 77 inside of boss 74 so as to extend coaxially with the oil tube 77. Since the tube 78 fits tightly in an aperture 79 in boss 74, and since the oil tube 77 fits tightly in a counter bore 80 for this aperture, it is evident that the flow of oil from pipe 72 is confined to an an-

nular chamber formed between the two tubes 77 and 78.

In Fig. 9 a permanently fastened frame 65 is shown, on which the oil burner 87 may be swung. Such a permanently attached frame is not an essential feature, since this frame itself may be pivoted and form a door. Such an alternative form is shown in Fig. 70 1, wherein the hinged door 94 replaces the construction shown in Fig. 9. This door 94 is swung on pivots 114. In order that the door 94 may be swung without interfering with the oil supply to the burner 87, a pipe 75 construction 115 is provided which has parts swinging on an axis substantially coinciding with that of the pivots 114. This pipe construction 115 is entirely similar to that described previously in connection with the 80 swinging of the burner 87, and for that reason it is not considered essential to describe this element in any greater detail. Suffice it to say that the supply and return pipes 51 and 67 connect to a pipe fitting 116 which 85 may be rotated about its axis relative to the stationary fittings 117 and 118. These fittings connect respectively to the supply pipe 119 and the return pipe 120. Should the necessity ever arise for gaining access to the 90 interior of the combustion chamber, a large opening thereto is readily available. Furthermore, there is no need for providing supplementary openings to the fuel chamber, as is common in other types of installation.

A pressure gauge 121 may be used in connection with the valve structure 59 to indicate the oil pressure produced therein by the pump 33.

I claim:

1. In an oil burner, a pivoted door, means for pivotally supporting the oil burner on the door, a stationary pipe, means rotatable relatively to the pipe and connecting therewith for conducting oil, the rotation being on the axis of movement of the door, and coincident therewith, and means leading from the rotatable means to the oil burner for supplying oil thereto.

2. In an oil burner, a pivoted door, an oil burner pivotally supported on the door in such a way that it projects through an aperture in the door, and means for supplying oil to the burner, comprising a pair of 105 relatively rotatable pipe fittings arranged with the axis of rotation coincident with that of the door, and another pair of relatively rotatable pipe fittings arranged with the axis of rotation coincident with that of 110 the burner.

In testimony whereof, I have hereunto set my hand.

TRAY DAVIS.
